(57) **CLAIM**

The ornamental design for a suction nozzle for vacuum cleaner, as shown and described.

DESCRIPTION

1. Suction nozzle for vacuum cleaner
1.1 is a perspective view of a Suction Nozzle for Vacuum Cleaner, showing our new design;
1.2 is a front elevation view thereof;
1.3 is a rear elevation view thereof;
1.4 is a left-side elevation view thereof;
1.5 is a right-side elevation view thereof;
1.6 is a top plan view thereof;
1.7 is a bottom plan view thereof; and
1.8 is a partially enlarged view of the portion in figure 1.1, wherein the stipple shading represents portions reflecting the light emitted from the LED formed in the suction nozzle. The evenly-spaced broken line shown in figures 1.1 and 1.3 through 1.6 is for the purpose of illustrating portions that do not form a part of the claimed design. The dot-dot-dash broken line in figure 1.8 surrounding the enlarged view forms no part of the claimed design.
